UNITED STATES PATENT OFFICE.

ABRAHAM NELKEN, OF CLEVELAND, OHIO.

DESIGN FOR A HAT OR CAP.

SPECIFICATION forming part of Design No. 27,523, dated August 17, 1897.

Application filed June 1, 1897. Serial No. 639,055. Term of patent 3½ years.

To all whom it may concern:

Be it known that I, ABRAHAM NELKEN, of Cleveland, Cuyahoga county, Ohio, have invented and produced a certain new and useful Design for Cap-Tops; and I do hereby declare the following to be a full, clear, and exact description of the invention, such as will enable others skilled in the art to which it pertains to make and use the same.

10 My invention relates to a new and original design for hats or caps; and it consists in the peculiar configuration and arrangement of parts, as will be hereinafter more fully set forth and claimed.

15 In the drawings, Figure I is a plan view illustrating my design as applied to a cloth Tam O'Shanter cap. Fig. II is a central cross-section.

The design consists in a central disk A, 20 surrounded by two or more contrasting concentric panels B B'. The panel B is preferably of a color or shade that contrasts with

the shade or color of panels A and B'. The disk A and panel B' have, preferably, the same shade or color. As shown in the drawings, I prefer to form the disk A and panel B with raised piping b^1 and provide the outer edge of the panel B' with a piping b^2 . The number of concentric rings B and B' is immaterial, and the essential features of the 30 design consist in the central disk and annular contrasting panels arranged concentrically in relation to said central disk.

What I claim is—

The design for a hat or cap, substantially 35 as herein shown and described.

In testimony whereof I sign this specification, in the presence of two witnesses, this 13th day of April, 1897.

ABRAHAM NELKEN.
